UNITED STATES PATENT OFFICE.

JAMES L. POALK, OF MERCHANTVILLE, NEW JERSEY, ASSIGNOR TO NEW CENTURY HOOK AND EYELET COMPANY, OF CAMDEN, NEW JERSEY, A CORPORATION OF NEW JERSEY.

DESIGN FOR A LACE-FASTENER.

SPECIFICATION forming part of Design No. 35,690, dated February 4, 1902.

Application filed December 16, 1901. Serial No. 86,168. Term of patent 14 years.

To all whom it may concern:

Be it known that I, JAMES L. POALK, a citizen of the United States, residing at Merchantville, in the county of Camden and State 5 of New Jersey, have invented and produced a new and original Design for a Lace-Fastener, of which the following is a specification, reference being had to the accompanying drawings, forming part hereof, in which—

10 Figure 1 is a top or plan view of a lace-fastener, showing the design of my said invention. Fig. 2 is an underneath plan view of the fastener. Fig. 3 is a side elevational view thereof, and Fig. 4 is a longitudinal sectional view on the line 4 4 of Fig. 1. These 15 four views are deemed essential to fully illustrate the shape or configuration of the lace-fastener of the design of my invention.

As illustrated in the drawings, the leading 20 or material feature of my invention consists of the shape or configuration of the fastener, and particularly the head thereof. As viewed in plan view, as in Fig. 1, the fastener has the 25 appearance of a ring *a*, from which projects tangentially a substantially straight projection *b*, having at its end a curved tailpiece *d*, the tailpiece being formed on an arc parallel to a portion of the periphery of the ring *a*,

and therefore substantially concentric with a portion of said ring *a*. As viewed in underneath plan view, as in Fig. 2, the under faces of the ring *a*, projection *b*, and the tailpiece *d* are shown as concave. As viewed in side elevation, as in Fig. 3, from the ring *a* projects downwardly an eyelet *e*, and the upper faces of the ring *a*, projection *b*, and tailpiece *d* are rounded or convex. As viewed both in end elevation and in section, as in Figs. 3 and 4, the projection *b* lies in the same plane as the ring *a*; but the tailpiece *d* 35 is elevated above said plane, being connected with the projection *b* by a curved shoulder *d'*.

Having thus described my invention, what I claim as new, and desire to secure by Letters 40 Patent, is—

The design for a lace-fastener, substantially as herein shown and described.

In testimony whereof I have hereunto set my signature in the presence of two subscribing 45 witnesses.

JAMES L. POALK.
